UNITED STATES PATENT OFFICE.

HART O. BERG, OF NEW YORK, N. Y.

TOILET-CASE.

SPECIFICATION forming part of Letters Patent No. 295,222, dated March 18, 1884.

Application filed July 30, 1883. (No model.)

To all whom it may concern:

Be it known that I, HART O. BERG, a citizen of the United States, and a resident of New York, in the county and State of New York, have invented a new and useful Improvement in Toilet-Cases, of which the following is a full, complete, and exact specification, reference being had to the annexed drawings, which form a part thereof.

The object of my invention is to construct a toilet-case which will serve at one time as a convenient receptacle for a brush, comb, and mirror, or other toilet articles, and at another can be used to hold collars, neckties, and other articles. This is accomplished by attaching to one side of the body and lid of the interior portion of the case a frame-work covered with any suitable material, as silk, &c., and then placing on the bottom of the cover and body of the case, beneath these frames, panels of pasteboard or other material, provided on their surfaces with the necessary projections for the reception and holding of such articles as brushes, combs, and mirrors.

In the annexed drawings, Figure I shows a perspective view of my case with the frames in a raised position, one of which is hinged to one side of the cover, and the other to one side of the body. Fig. II is a vertical transverse section of the case, showing the panels and frames. Figs. III and V are plan views of the panels. Fig. IV is a longitudinal sectional view of Fig. III.

Similar letters refer to similar parts throughout the drawings.

In the drawings, M indicates the frames, which are ordinarily made of wood, of a size conformable to that of the box to which they are attached, and are covered very loosely with satin, silk, or other material. These frames are suitably hinged to one side of the bottom of the body and cover of the case. The cover of the case is indicated by O and the body by N.

When it is desired to use the case as a receptacle for a brush, comb, and mirror, the frames M are lifted up a short distance, and on the bottom of the body and cover are placed, respectively, the panels K and P, which are provided on their surfaces with suitable projections for the reception, in the body of the case, of the comb and brush, and, on the cover,

of the mirror. The frames M are then closed down on the panels and in the projections on the surfaces of the panels, which now rest in and are covered by the satin or other material of the frame M. The various articles—as comb and brush—are placed and secured in the body, while a mirror is secured to the cover. If it is desired to use the case for the reception of other articles than a brush, comb, or mirror, it will be necessary, of course, to alter the projections on the surfaces of the panels.

When the case is to be used for holding neckties, gloves, or collars, or other similar articles, the frames are uplifted and the panels K and P are removed. The frames are then restored to their original position, and in this way afford a neat background for the case.

The advantage which results from the use of my improvement is that I am able to accomplish what I desire in a more convenient manner than is attained by other inventions of a similar class.

By using the frames M loosely covered by silk, satin, or other suitable material, and inserting between them and the bottom of the case the panels K and P, I am able to economize in the use of material and in the construction of the case. In other inventions separate trays are necessary for the comb, brush, and mirror, and a separate surface of silk or satin in addition for the bottom of the case when the trays are removed, in order that the case may serve as a neat and fit receptacle for collars, neckties, and other similar articles, while in my invention the satin-covered frames M, when resting on the panels K and P, provide means for holding in position a brush, comb, or mirror, and when the panels are removed without necessitating the employment of any other arrangement, they form a desirable and pretty background for the case when it is used for collars and neckties, as well as a covering for the bottom of the case.

What I claim as new, and desire to secure by Letters Patent, is—

1. A toilet-case provided on its interior with frames attached to one side of the body and cover, and covered with satin or any other suitable material, and removable panels in-

serted between the frames and the bottom of the body and cover of the case, having on their surfaces the requisite projections for holding and securing toilet articles, substantially as described.

2. In a toilet-case, the combination of the frames M, the body N, the cover O, and the

removable panels K and P, substantially as described and set forth.

HART O. BERG.
